UNITED STATES PATENT OFFICE.

GEORGE H. SARGENT, OF TORONTO, ONTARIO, CANADA, ASSIGNOR TO UNDERWOOD ELLIOTT FISHER COMPANY, OF NEW YORK, N. Y., A CORPORATION OF DELAWARE.

TYPEWRITING MACHINE.

Application filed April 28, 1926. Serial No. 105,086.

This invention relates to improvements in typewriting machines for typing on fan-fold webs or loose multi-ply web-forms.

In the patent issued to George W. Renz, No. 1,503,064, of June 16, 1923, is shown a machine equipped with a twin carbon-carrier for accommodating two separate webs or packs, either of which may be used while the other is idle, said webs having printed thereon different work-forms, it being only necessary to fold or loop the leading end of the not wanted web backward with its interleaved carbon-sheets through the carbon-carrier, while the wanted web-form is being typed.

The present invention embodies an improvement on the twin carbon-carrier by using a single carbon-carrier of standard form and novel means for rendering its use efficient in handling the two webs.

According to this improvement the carbon-carrier effects a shifting of the carbon-sheets, as usual. It moves forwardly with the webs during line-feeding and may be forced backwardly by a carriage, to which it is detachably connected; the backwardly-moving carriage being effective to strip the carbons from typed forms to new forms while carrying the idle backwardly-looped work-web with it. During this stripping operation, the active web is found to contact with the idle web and thereby move the plies thereof out of registration, sometimes to such an extent that it interferes with the operation of the active web, and in any event requires a readjustment of the plies of the idle web before it can be inserted around the platen for typing. It is one of the objects of the present invention to prevent this fouling between the used and idle web-forms. To this end, a broad shelf or separating plate is preferably mounted on a step of said standard carbon-carrier, and positioned between the two sets of work-webs.

When the upper work-web is to be typed upon, the leading end of the lower web may be folded or turned backwardly under the separating shelf, which acts as a guide; while when the lower web is to be typed upon the upper one is accordingly folded back over the separating shelf, which is extended forwardly from its supporting carbon-carrier to an extent sufficient to prevent contact of the web-form units at all times.

Heretofore when removing work-webs, it

was necessary to remove the interleaved carbon-sheets therefrom, and to draw or pull said webs backwardly out of the machine. This was required because the guide cross-rods or bars at the rear of the machine were fixed in the frame. To obviate the necessity for expenditure of time and labor in changing work-webs is another object.

A feature of the invention therefore resides in the provision of detachable guide means whereby a web-form, when once interleaved with carbon-sheets, may retain or carry its carbons in operative relation at all times, on or off the machine, and until the web-strip is used up.

The guide means above referred to preferably consists of a yoke-shaped direction or guide bar, having angular end legs or extensions formed with reduced terminals to provide pins to be received in bores or holes near the ends of the usual fixed lower guide-bar at the rear of the machine, to support the yoke-shaped guide-bar in parallel detachable relation thereover.

When it is desired to thread a new set of work-webs into the machine, the lower web is fed forward over the lower fixed bar, while the upper web is passed forward over the upper detachable bar; and so, when it is desired to remove a pair or set of webs from the machine, the upper guide-bar may be raised or detached from the lower fixed bar, after which both webs, with their carbon-carrier (which is also detachable), may be removed as a unit from the machine, the carbon-sheets remaining in interleaved relation with the work-web plies. Then another set of work-webs carrying different interleaved carbon-sheets, and their carrier, may be placed as a unit in the machine, and one of the set fed around the platen to the typing position, thus speeding up the work.

It will be appreciated that the separating plate and the removable guide-bar operate to maintain the two sets of work-webs separated to prevent the possibility of fouling of one by the other during the carbon-stripping operation, when the idle web moves relatively to the active or typed web.

Other features and advantages will herein-after appear.

In the accompanying drawings,

Figure 1 is a longitudinal sectional elevation of the machine with the devices attached and showing one of the work-webs in typing.

position, and the other turned or folded back under the web-separating plate carried on the detachable carbon-carrier.

Figure 2 is a plan view of the carbon-carrier, showing how the web-separating plate is mounted on a step thereof.

Figure 3 is a detail perspective view, of the web-separating plate and its supporting member.

Figure 4 is a detail perspective view, showing the detachable guide-bar and its supporting companion-bar.

Referring in detail to the drawings, the usual platen 10 is mounted to revolve in its supporting carriage 11, at the back of which is mounted a work-frame 12. Feed-rolls 13 and 14 co-operate with the platen in the usual manner to feed the work-webs in the operation of the machine. Mounted on the frame 12 is a carriage 15, including a bed-plate 16, carrying rollers 17, engaging rails 18, by which the carriage is guided in its reciprocatory movements, toward and away, from the platen during feeding and carbon-stripping operations.

On the bed-plate 16 is mounted the carbon-carrier 19, which includes a base-plate 20 resting flat on said bed-plate and having pins 21, which project downwardly through corresponding openings 22 in the bed-plate and which are formed with slots or kerfs 23 to receive keys 24 to lock the plates together. The keys are pivoted at 25 so that the carbon-carrier may be readily disconnected from the bed-plate of the carriage by swinging the keys out of engagement with the slots, when it is desired to remove the carbon-carrier and its set of work-webs from the machine.

The usual push bar 26 is provided to facilitate the backward movement of the carbon-carrier when withdrawing the carbon-sheets from a typed section of the work-web.

The usual stepped blocks 27 of the carbon-carrier support the usual carbon-blades 28, arranged in the usual staggered relation, and to which the carbon-sheets 28' are attached in the usual manner.

As here shown, the carbon-blade-supporting blocks 27 have steps or elevations, and, to the third or middle step of one block, I mount a separator-plate 29 carried by a clip-bar 30, which is extended at one end and apertured as at 31, through which aperture a screw or pin 32 is passed to secure the bar and its plate in operative position between the work-web of the set.

The plate has a bent guide-portion 33 to facilitate the passage of the leading end of the lower work-web when it is turned back under the plate and drawn backwardly through the carbon-carrier as in Figure 1.

At the rear of the machine is arranged the usual fixed direction bar 34, over which the lower work-web 35 is fed into the machine between guides 36 carried thereon. Outside of

the guides the bar 34 is provided with apertures 37 which loosely receive pins or reduced extensions 38 of legs or end portions 39 of a direction or guide-bar 40, over which the upper work-web 41 of the set is fed into the machine.

Obviously the bar 40 is readily detachable from its supporting fixed bar 34, so that both work-webs may be lifted from the machine with their associated carbon-carrier when it is desired to substitute another carbon-carrier having similar work-webs, or a single work-web of many plies.

Certain features disclosed herein are claimed in the application of John Waldheim, Serial No. 684,127, filed January 3, 1924; the claims in this application being limited to features not disclosed in said Waldheim application.

Variations may be resorted to within the scope of the invention, and portions of the improvements may be used without others.

Having thus described my invention, I claim:

1. The combination with a typewriting machine having a platen and means for feeding one of a set of two work-web packs around said platen, and a carbon-carrier including carbon-carrying blades having carbons interleaved with the work-webs of both packs, the other pack being tucked back between the blades in a reverse idle loop, of a separator attached to the carrier and positioned between the packs to direct the active webs away from the idle webs so as to prevent friction between the active and idle packs when the carrier is moved rearwardly to strip the carbons of the active webs, and means mounted rearwardly of the carrier for separating the packs to prevent contact of the same as one moves relatively to the other during the carbon-stripping operation, said separator including a plate extending beyond the forward edges of the immediately adjacent carbon-blades to shield said idle loop from contact with the active pack.

2. The combination with a typewriting machine having a platen and means for feeding one of a set of two work-web packs around said platen, and a carbon-carrier including carbon-carrying blades having carbons interleaved with the work-webs of both packs, the other pack being tucked back between the blades in a reverse idle loop, of a separator attached to the carrier and positioned between the packs to direct the active webs away from the idle webs so as to prevent friction between the active and idle packs when the carrier is moved rearwardly to strip the carbons of the active webs, means mounted rearwardly of the carrier for separating the packs to prevent contact of the same as one moves relatively to the other during the carbon-stripping operation, and a mounting bar for said separator, said bar being inter-

changeable with any of said carbon-blades to vary the number of carbons and webs in each pack.

3. The combination with a typewriting machine having a platen, a detachable carbon-carrier, and means for feeding one of a plurality of work-webs around the platen, of a clip-bar secured to said carrier between the work-webs, and a separator-plate supported thereby in a horizontal position, said plate extending over the width of said webs and forwardly of said carrier and being provided at its forward edge with a bent guide-portion for the lower web.

15 4. In combination with a typewriting machine having a platen, a detachable carbon-carrier, and means for feeding one of a set of work-webs interleaved with carbon-sheets around the platen, a clip-bar mounted on a 20 step of the carrier, and a horizontally-arranged separator-plate carried by said clip-bar and extending forward between the webs to prevent contact one with the other.

5. In combination with a typewriting machine having a platen, a carbon-carrier, including carbon-blades, and a feed-roll mechanism to feed a work-web including a plurality of plies, or one of a set of two work-webs interleaved with carbon-sheets around 30 the platen, while the other one of the set is folded back in idle position between the carbon-blades, a separator and guide-plate positioned between the sets to prevent contact one with another, and a clip-bar engaging 35 the rear edge of the plate and by which said plate is supported from a step of the carrier to move therewith.

6. The combination with a typewriting machine having a platen and means for feeding 40 one of a set of two work-web packs around said platen, and a carbon-carrier including carbon-carrying blades having carbons interleaved with the work-webs of both packs, the other pack being tucked back between the 45 blades in a reverse idle loop, of a separator attached to the carrier and positioned between the packs to direct the active webs away from the idle webs so as to prevent friction between the active and idle packs when the 50 carrier is moved rearwardly to strip the carbons of the active webs, and means mounted rearwardly of the carrier for separating the packs to prevent contact of the same as one moves relatively to the other during the carbon-stripping operation, said last-mentioned 55 means including a guide-bar for the lower of said packs and a second guide-bar for the upper pack spaced vertically and horizontally from the first-mentioned guide-bar, both 60 bars being effective to guide the webs from the source of supply to the carbon-carrier.

7. In a typewriting machine having a platen and a carriage, means for manifolding either a single web having very many plies, 65 or two superposed webs each having fewer

plies, including a single carbon-carrier equipped with carbon-carrying blades for stripping the carbons along the plies of the web, said carbon-carrier being of standard construction and capable of stripping the carbons between the plies of either the web having many plies or the upper and lower webs each having fewer plies, a separator to prevent fouling of the upper web upon the lower web whenever that is folded back between the carbon-carrier blades and the upper web is shifted relatively to the lower web and vice versa, said carbon-carrier including a stepped series of mounts for supporting the ends of the blades which carry the carbons, said separator being supported upon one of said mounts, and means located at the rear of the carrier for keeping said webs separated to prevent friction therebetween during the carbon-stripping operation.

8. In a typewriting machine having a platen and a carriage, means for manifolding either a single web having very many plies, or two superposed webs each having fewer plies, including a single carbon-carrier 90 equipped with carbon-carrying blades for stripping the carbons along the plies of the web, said carbon-carrier being of standard construction and capable of stripping the carbons between the plies of either the web having many plies or the upper and lower webs each having fewer plies, a separator to prevent fouling of the upper web upon the lower web whenever that is folded back between the carbon-carrier blades and the upper web is shifted relatively to the lower web and vice versa, said carbon-carrier including a stepped series of mounts for supporting the ends of the blades which carry the carbons, said separator being fixed to one of said carbon-carrying blades and detachably held thereby upon one of said mounts, whereby the number of carbons and plies in each web may be varied, and means located at the rear of the carrier for keeping said webs separated to prevent friction therebetween during the carbon-stripping operation.

9. In a typewriting machine having a platen and a carriage, means for manifolding either a single web having very many plies, 115 or two superposed webs each having fewer plies, including a single carbon-carrier equipped with carbon-carrying blades for stripping the carbons along the plies of the web, said carbon-carrier being of standard 120 construction and capable of stripping the carbons between the plies of either the web having many plies or the upper and lower webs each having fewer plies, a separator to prevent fouling of the upper web upon the lower web whenever that is folded back between the carbon-carrier blades, and the upper web is shifted relatively to the lower web and vice versa, said separator having a smooth, continuous surface, thereby also serving as a 130

guide for directing the leading edge of the lower idle web rearwardly to pocket it within the carbon-carrier, out of the way of the upper web, and means located at the rear of the carrier for keeping said webs separated to prevent friction therebetween during the carbon-stripping operation.

10. In a typewriting machine, the combination with a platen and a carriage, of a web-manifolding mechanism including a truck in the rear of the platen, a carbon-carrier detachably mounted upon said truck to be removed from the machine bodily together with the web or webs thereon, said carbon-carrier having means for separating the upper active web from the lower web when the latter is idle, a guiding bar over which the lower idle web runs at the intake end of the machine, and a second guiding bar above the first and over which the upper web runs at the intake side of the machine, the upper guiding bar being detachable whereby the upper guiding bar and the carbon-carrier may be removed from the machine to permit the use of another carbon-carrier for a web requiring the full capacity of the carbon-carrier, said upper guiding bar being in the form of a yoke having the ends thereof reduced and received in sockets in the lower guiding bar.

15. In a typewriting machine, the combination with a platen and a carriage, of a web-manifolding mechanism including a truck in the rear of the platen, a carbon-carrier detachably mounted upon said truck to be removed from the machine bodily together with the web or webs thereon, said carbon-carrier having means for separating the upper active web from the lower web when the latter is idle, a guiding bar over which the lower idle web runs at the intake end of the machine, and a second guiding bar above the first and over which the upper web runs at the intake side of the machine, the upper guiding bar being detachable whereby the upper guiding bar and the carbon-carrier may be removed from the machine to permit the use of another carbon-carrier for a web requiring the full capacity of the carbon-carrier.

20. In a typewriting machine, the combination with a platen and a carriage, of a web-manifolding mechanism including a truck in the rear of the platen, a carbon-carrier detachably mounted upon said truck to be removed from the machine bodily together with the web or webs thereon, said carbon-carrier having means for separating the upper active web from the lower web when the latter is idle, a guiding bar over which the lower idle web runs at the intake end of the machine, and a second guiding bar above the first and over which the upper web runs at the intake side of the machine, the upper guiding bar being detachable whereby the upper guiding bar and the carbon-carrier may be removed from the machine to permit the use of another carbon-carrier for a web requiring the full capacity of the carbon-carrier.

25. In a typewriting machine, the combination with a platen and a carriage, of a web-manifolding mechanism including a truck in the rear of the platen, a carbon-carrier detachably mounted upon said truck to be removed from the machine bodily together with the web or webs thereon, said carbon-carrier having means for separating the upper active web from the lower web when the latter is idle, a guiding bar over which the lower idle web runs at the intake end of the machine, and a second guiding bar above the first and over which the upper web runs at the intake side of the machine, the upper guiding bar being detachable whereby the upper guiding bar and the carbon-carrier may be removed from the machine to permit the use of another carbon-carrier for a web requiring the full capacity of the carbon-carrier.

30. In a typewriting machine, the combination with a platen and a carriage, of a web-manifolding mechanism including a truck in the rear of the platen, a carbon-carrier detachably mounted upon said truck to be removed from the machine bodily together with the web or webs thereon, said carbon-carrier having means for separating the upper active web from the lower web when the latter is idle, a guiding bar over which the lower idle web runs at the intake end of the machine, and a second guiding bar above the first and over which the upper web runs at the intake side of the machine, the upper guiding bar being detachable whereby the upper guiding bar and the carbon-carrier may be removed from the machine to permit the use of another carbon-carrier for a web requiring the full capacity of the carbon-carrier.

35. per active web from the lower web when the latter is idle, a guiding bar over which the lower idle web runs at the intake end of the machine, and a second guiding bar above the first and over which the upper web runs at the intake side of the machine, the upper guiding bar being detachable whereby the upper guiding bar and the carbon-carrier may be removed from the machine to permit the use of another carbon-carrier for a web requiring the full capacity of the carbon-carrier, said upper guiding bar being in the form of a yoke having the ends thereof reduced and received in sockets in the lower guiding bar.

40. 12. In a typewriting machine having a platen and a carriage, means for manifolding either a single web having very many plies, or two superposed webs each having fewer plies, including a single carbon-carrier equipped with carbon-carrying blades for stripping the carbons along the plies of the web, said carbon-carrier being of standard construction and capable of stripping the carbons between the plies of either the web having many plies or the upper and lower webs each having fewer plies, a separator to prevent fouling of the upper web upon the lower web whenever that is folded back between the carbon-carrier blades and the webs are shifted relatively to each other, and means located at the rear of the carrier for keeping said webs separated to prevent friction therebetween during the carbon-stripping operation.
